D. BARNARD.

MEANS FOR REGULATING THE TEMPERATURE OF AIR FED TO CARBURETERS.

APPLICATION FILED NOV. 8, 1910.

1,032,582.

Patented July 16, 1912.

UNITED STATES PATENT OFFICE.

DAVIS BARNARD, OF LOS ANGELES, CALIFORNIA.

MEANS FOR REGULATING THE TEMPERATURE OF AIR FED TO CARBUREETERS.

1,032,582.

Specification of Letters Patent. Patented July 16, 1912.

Application filed November 8, 1910. Serial No. 591,307.

To all whom it may concern:

Be it known that I, DAVIS BARNARD, a citizen of the United States, residing at Los Angeles, California, have invented a new and useful Means for Regulating the Temperature of Air Fed to Carbureters, of which the following is a specification.

This invention relates to improved means for supplying carbureters with air heated to a predetermined degree such as is necessary to properly vaporize fuels of different degrees of specific gravity.

The invention provides for automatically regulating the degree of heat of the air which is fed to the carbureter, such air being drawn partially from a body heated by the engine, such for example, as the cylinder, or other heated portion of the engine, and partially from the outer atmosphere, the appliance automatically governing the proportions or volumes of air fed from these two sources so that the resulting blended current of air supplied to the carbureter is automatically maintained at any desired degree.

The above features of the invention are supplemented by means for positively predetermined the degree of heat at which the appliance will maintain the current of air fed to the carbureter after it has once been set as desired.

Various means may be employed for constructing a device embodying the general principles just mentioned.

A desirable arrangement for controlling a mixture of the hot and cold air is illustrated in the drawings which show an inlet tube having a plurality of lateral openings therethrough, means on the outside of said tube for regulating the circumferential extent of said openings, and means on the inside of the tube to automatically control the lengthwise extent of said openings. The means last mentioned may be operated by any desirable known thermostatic construction, a convenient device for the purpose being illustrated in the drawings.

Referring to the accompanying drawings, which illustrate the invention, Figure 1 is a mid-section of the appliance; Fig. 2 is an enlarged sectional detail of a portion of Fig. 1; Fig. 3 is a transverse section on line $\alpha-\alpha$ of Fig. 1, parts being broken away; Fig. 4 is a detail side elevation with parts broken away; Fig. 5 is a side elevation on a re-

duced scale showing the appliance connected up to an engine and carbureter; Fig. 6 is a perspective view of the regulating shutter showing also part of the inlet tube therebeneath.

Referring in detail to the drawings, with in a chamber which is desirably formed by a drum-shaped casing 1, is mounted a thermostatic device consisting of a series of flat transverse containers 2 desirably made up of each of two dish-shaped disks fastened to each other with their concave sides facing and riveted together along their peripheries. Said containers 2 must be made of thin resilient material and must be hermetically sealed so that the contraction and expansion of the air in them will cause the thermostat to operate properly. The uppermost of the containers 2 is suspended from the center of the drum-head 4 by means of a rod 5 the position of which is regulated by the milled head 6 and a locking nut 7. Each of the intermediate containers 2 is connected together at proper distances from each other by means of separate rods 8 having reduced end portions 9 which project through the adjacent walls of the containers and are riveted down to connect the containers and make an air tight fitting.

From the lower side of the lowermost container extends an operating rod 11 connected to a valve head or damper 12. Said valve head 12 has a skirt 13 which fits within the inlet tube 14. Through said inlet tube 14 leads a series of inlet openings 16 which are more or less closed by means of a shutter 17 fitting over said tube and having cut-away portions or openings 18 which may be brought wholly or partially into register with said inlet openings 16. The tube 14 for admitting cold air to the device is contracted at 14' to form a valve seat for the valve head 12. When the air within casing 1 becomes overheated, the air within the containers 2 becomes hot and expands, forcing farther apart the disks which form said containers and thereby lowering rod 11 so that skirt 13 comes below the air inlets 16. In order to accurately control the position of said shutter and guard against displacement thereof, a retaining spring 19 is provided thereon, said spring having an arm 20 the end of which engages a series of notches 21 formed on the outside of the inlet tube 14. In order to keep said shutter 17 from sliding

up or down out of place stops or pins 22 may be provided.

From the inlet tube 14 a passage 25 leads around to the side of the drum 4 where it 5 opens into the hot air inlet 26. This inlet, in the illustrated embodiment of the invention, draws in heated air from a jacket 27 that surrounds the exhaust pipe 28 of the engine 29. At the lower end of said jacket 10 there is an annular intake opening 30 around the pipe 28, the heated air being drawn from near the closed upper end of said jacket. From the other side of drum 1 leads the pipe 31 which communicates with the 15 carbureter 32. The shutter 17 is circumferentially adjusted to allow a greater or less intake of cold air according to whether a more or less volatile liquid fuel is used. The upper container of the thermostat may 20 be swiveled to the rod 5 by means of a clip 33 which surrounds a flange 34 on the lower end of the rod.

When the engine is started the thermostat will be in the position shown in Fig. 1 holding the damper up and thus closing all the 25 air inlets. By a proper rotation of rod 5 by its milled head 6, said rod being threaded through the top wall of the casing, the normal position of the containers of the thermostat may be so regulated that the variations 30 of heat within the thermostat will cause the damper 12 to move up and down in the manner necessary to secure a proper automatic regulation of the temperature of 35 the air supplied to the carbureter.

I claim:

1. In a thermostatic air regulator, a hot air supply, a casing provided with a chamber for blending hot and cold air, a hot air 40 tube to conduct hot air from said supply into said chamber, a cold air supply passage opening into said hot air tube near the mouth thereof, a cold air inlet tube or cylinder with which said passage communicates, said inlet tube having lateral inlet openings, a damper to vary the size of said 45 openings from within said tube, a thermostat within the blending chamber, and an operating rod working through the wall of 50 said chamber and operatively connecting said thermostat and damper.

2. In a thermostatic air regulator, a hot air supply, a casing provided with a chamber into which air is conducted from said 55 supply, a tube to conduct cold air into said chamber to blend the cold air with the heated air therein, said tube having lateral inlet openings, an external shutter to control the size of said openings as pre-deter- 60 mined, a damper to vary the size of said openings from within said tube, a thermostat to operate said damper, and means to

conduct air from said chamber to a place of use.

3. In a thermostatic air regulator, a cas- 65 ing, means to conduct cold air to said casing, means to conduct heated air to said casing, one of said means being provided with an inlet, the opening of said inlet being regulated from one side by a manually operable shutter, and from the other side by a thermo- 70 statically operative damper, and a thermostat to control said damper.

4. In a thermostatic air regulator, in com- 75 bination, a blending chamber, means to conduct heated air therefrom to a place of use, an inlet tube to conduct cold air to said blending chamber, said tube having lateral openings, a longitudinally movable damper, a thermostat to move said damper in oppo- 80 site directions to control the size of said openings from the inside of said tube, and a circumferentially adjustable shutter to control the size of said openings from the outside of said tube. 85

5. In a thermostatic air regulator, in com- 90 bination, means to conduct heated air to a place of use, means for blending cold air with said heated air during its movement toward the place of use, said blending means comprising an inlet tube to conduct cold air thereto, said tube having lateral openings, said tube being contracted to form a valve seat on the delivery side of said openings, a damper within said tube to regulate the 95 size of said openings, said damper comprising a valve to fit said valve seat, a skirt depending from said valve to close said opening, and means to thermostatically operate said damper. 100

6. In a thermostatic air regulator, the combination, with a blending chamber and thermostat therein, of an inlet tube to supply cold air for said chamber, said tube having lateral openings, a damper within 105 said tube, said damper being controlled by said thermostat to regulate the size of said openings from the inside of said tube, a circumferentially adjustable shutter to regulate the size of said openings from the outside of said tube, and a spring arm carried by said shutter, the free end of said arm engaging said tube to hold said shutter yield- 110 ingly in the adjusted position.

In testimony whereof I have hereunto 115 signed my name in the presence of two sub- scribing witnesses at Los Angeles, in the county of Los Angeles and State of California, this third day of November 1910.

DAVIS BARNARD.
